UNITED STATES PATENT OFFICE.

CLAUDE FLAGLER, OF BAY CITY, MICHIGAN, ASSIGNOR TO THE QUAKER SHADE ROLLER COMPANY, OF BAY CITY, MICHIGAN.

MACHINE FOR FERRULING SHADE-ROLLERS.

SPECIFICATION forming part of Letters Patent No. 759,360, dated May 10, 1904.

Application filed October 29, 1903. Serial No. 178,996. (No model.)

To all whom it may concern:

Be it known that I, CLAUDE FLAGLER, a citizen of the United States, residing at Bay City, in the county of Bay and State of Michigan, 5 have invented certain new and useful Improvements in Machines for Ferruling Shade-Rollers; and I do hereby declare the following to be a full, clear, and exact description of the invention, such as will enable others 10 skilled in the art to which it appertains to make and use the same.

This invention is a machine for attaching metal ferrules to the ends of shade-rollers and for depressing the edge of the ferrule where 15 it overlaps the roller, so that the ferrule edge will not project above the surface of the roller.

The improvements consist in the parts, their combination and operation, and the equivalents thereof, as will be fully set forth 20 in the specification and claims of this application.

The mechanisms comprising the machine are arranged to perform the following functions: First, to reduce the diameter of one 25 end of the shade-roller by compressing the fibers of the roller to such an extent that a ferrule having its outside diameter equal to the diameter of the roller will fit over the compressed end, then to force the end of the 30 roller into the ferrule, then to compress the circumference of the ferrule at its inner end, so as to crimp the ferrule end into the roller, and thus lock the ferrule against coming off the roller.

With these objects in view, together with certain others that will appear later in this specification, the machine consists in the combination of devices illustrated in the accompanying drawings, in which—

Figure 1 is a side elevation of the ferruling-machine. Fig. 2 is a top plan view of the same. Fig. 3 shows in perspective the end of a roller and the ferrule which is to be fitted to it by the machine. Fig. 4 shows the end 45 of the roller with the ferrule attached. Figs. 5, 6, and 7 are respectively part sectional views illustrating the various steps by which the ferrule is secured to the roller. Fig. 8 is a horizontal sectional view of the ferruling-

dies and the mechanism that operates them. 50 Fig. 9 is a front view of the die-plate shown in Fig. 8. Fig. 10 is a detail of the mechanism for opening and closing the compressing-dies. Fig. 11 is a front view of the same. Fig. 12 is a detail of the ferrule-plunger and 55 the cam that operates it. Fig. 13 is an end view of the plunger. Figs. 14 and 15 are face views of the cams that operate the compressing-dies, and Fig. 16 is a face view of the cam that operates the ferrule-plunger. 60 Fig. 17 is a side elevation of the mechanism for imparting intermittent movement to the conveyer that introduces the rollers into and ejects them from the machine. Fig. 18 is a side elevation of the ratchet shown in Fig. 17. 65 Fig. 19 is a side elevation, broken away in part, showing the roller-driving plunger and the devices that operate it. Fig. 20 is a side view of the friction-brake for limiting the movement of the conveyer. Fig. 21 is a front 70 view of the same. Fig. 22 is a vertical section taken on the line $y-y$ of Fig. 2, showing in side elevation the conveyer for feeding the rollers into and ejecting them from the machine. 75

The object of the machine, as has been indicated, is to automatically feed a roller and a ferrule into proper alinement in the machine, then to force the end of the roller through an opening of slightly-smaller diameter than the roller and into the ferrule, then to further compress the end of the ferrule preferably clear around its circumference, and then to discharge the ferruled roller from the machine. Having these objects in mind, the 85 general operation of the machine can be better understood by reference to Figs. 3, 4, 5, 6, and 7 of the drawings, in which 1 is the end of the roller to be ferruled, and 2 is the pawl-plate to be held against the end of the 90 roller by the ferrule, and 3 is the ferrule, which is preferably a thin cylindrical shell that may be provided, if desired, with an annular flange 3^a at one end to hold the pawl-plate 2 in place. In order to make the completed roller of the 95 same diameter from end to end, the outside diameter of the ferrule is preferably made the same as the outside diameter of the roller.

Hence the inside diameter of the ferrule will be somewhat less than the diameter of the roller, and the latter must be reduced before the ferrule can be slipped over it. I reduce 5 the end of the roller by forcing it through an opening 4^a, formed in a pair of dies 4, the opening being of the same diameter as the inside diameter of the ferrule 3. The edges of the dies 4 are preferably rounded or tapered, 10 so that the fibers of the roller will be compressed and not torn when the end of the roller is forced through the opening. The ferrule-plunger 5 holds the ferrule 3 in place just back of the opening 4^a, and when the end 15 of the roller 1 passes through the opening it immediately enters the ferrule 3. In practice this is done very quickly, almost with the rapidity of a blow. The end of the roller at this stage of the operation is in the position 20 indicated in Fig. 5. The next movement is to push the ferrule-plunger 5 toward the dies 4 a short distance, thus forcing the end of the ferrule 3 through the opening 4^a, compressing the metal of the ferrule and crimping its edges 25 into the fibers of the roller to form a circumferential depressed bead that effectually locks the ferrule in place. This movement is indicated in Fig. 6. After the edge of the roller has been crimped the jaws 4 of the die separate, as shown in Fig. 7. The ferrule-plunger 5 advances still farther and ejects the roller and ferrule from the opening 4^a.

Having described the general mode of operation, I will now point out the mechanisms 35 by which these operations are timed and effected in proper order, but with extreme rapidity.

The working parts of the mechanism are mounted on any suitable frame, as 6. In Figs. 40 1 and 2 the mechanism that accomplishes the ferruling is shown at the left-hand side, and the mechanism for automatically feeding the rollers into and discharging them from the machine is shown at the middle and right-hand 45 side.

I will first describe the device for feeding the rollers into the machine. This device is illustrated in Figs. 1 and 2. 7^a are sprocket-chains mounted on suitable wheels 7^a and carrying curved bracket 7^b, into which the rollers are fed either by hand or from a suitable hopper. The chains 7 carry each roller across the bed of the machine, stopping it in direct alignment with the die-opening 4^a long enough 55 for the ferruling operation to be performed. The chain then advances to feed the next roller into position. Intermittent step-by-step movement is imparted to the chain 7 by the device illustrated in Figs. 2, 17, and 18, where 8 is 60 the driving-shaft, to which the sprockets 7^a are fixed, and 8^a is a ratchet-wheel mounted thereon. The ratchet-wheel is operated by a pawl 9, mounted on a bell-crank lever 10, the free end of which engages the end of the arm 11, 65 pivotally mounted on the frame of the ma-

chine by means of a pin or pivot 11^a and having an up-and-down movement. The other end of the arm 11 engages the outer end of the bell-crank lever 12, the opposite end of which contacts with a moving part of the mechanism—as, for instance, the pin or wiper 13^a—that projects from the face of the disk 13, which operates the ferrule-plunger 5. The spring 14 is attached to the bell-crank lever 12 to restore it to its original position after 70 being displaced by the wiper 13^a. As the disk 13 revolves the wiper 13^a operates through the levers to move the ratchet 8^a one tooth forward, thus operating the chain 7 to bring the next roller into alignment with the die-opening 4^a. In order to prevent the chain 7 from moving too far, a friction-wheel 15 is fixed to the shaft 8, and a friction-band 15^b of any suitable form, secured to the frame 6, is passed around the wheel 15 and provided with the 85 clamping-screw 15^b, whereby its frictional effect may be regulated. When the roller comes into alignment with the opening 4^a, its end is immediately forced into the opening, as previously described. This movement is accomplished by means of the driving-plunger 16. (Shown in Figs. 1 and 2 and further detailed in Fig. 9.) The plunger is preferably mounted on a spindle 16^a, slidably mounted in suitable bearing 16^b, and I prefer to employ 90 the mechanism shown in Fig. 19 to give it the necessary forward driving movement and recoil. An upright lever 17, pivotally mounted at its lower end to the frame 6, is pivotally connected at its upper end to the spindle 16^a. 100 A link 17^a connects this lever with a similarly-mounted upright lever 18, the free end of which is adapted to be contacted by any suitably-timed moving part of the machine. The wiper 13^a is well adapted to this purpose, and 105 I therefore prefer to mount the lever 18 so as to engage this wiper at the proper time. By placing the lever 18 on that side of the center of the disk 13 opposite the lever 12 the wiper 13^a will first operate the lever 12, 110 moving the roller into alignment with the die-opening 4^a, and then will engage the end of the lever 18 and operate the plunger 16 to force the end of the roller into the opening. The plunger is restored to its original position 115 by the coiled spring 18^a or any suitable device. 120 Having described the means by which the roller is first brought into alignment with the die-opening and then forced a short distance into the opening, I will now describe the means by which the ferrule is brought into alignment with the end of the roller and held while the roller is forced into it, and then the end of the ferrule is crimped, after which the opening 4^a is increased in size and the 125 roller is ejected therefrom. The devices by which these results are attained are illustrated in Figs. 1, 2, and 8 to 16, inclusive, where 19 is the driving-shaft mounted in suitable bearings in the frame of the machine, and 19^a is a 130

gear-wheel revolvably mounted on the shaft, but adapted to be locked thereto when desired. The wheel 19^a may be driven by any suitable driving-pinion. The disk 13 is keyed to the 5 shaft and carries a suitably-shaped cam-groove 13^b, which engages a projection 20 slidably mounted in horizontal guides 20^a and adapted to operate the ferrule-plunger 5 toward and from the dies 4 in the manner previously described. By properly shaping the cam-groove 13^b, the movement imparted to the plunger 5 is such that it first draws back to permit the insertion of a ferrule in the space 5^a between its end and the dies 4. The 10 ferrule may be inserted by dropping from a suitable chute into which a number of ferrules may be fed at a time. The chute is omitted from the drawings for the sake of clearness. The plunger 5 remains stationary while the 15 driving-plunger 16 forces the end of the roller into the ferrule, and after the plunger 16 draws back the plunger 5 forces the ferrule into the dies a short distance to effect the crimping of the ferrule edge. At this instant 20 the dies 4 open and the plunger 5 pushes the ferrule and roller out of the jaws. It will be noted that the dies 4 remain closed except at the instant when the crimping is accomplished. They are closed when the end of 25 the roller is forced into the opening 4^a and closed when the plunger 5 forces the ferrule back to crimp its edge; but they then suddenly open to permit the uncompressed body of the ferrule to be discharged through them. 30 To accomplish this movement, I mount the dies 4 on suitable guides 6^a and connect them by means of suitable toggle-links 21 to slidable bars 21^a, which carry at their rear ends projections 21^b, adapted to engage suitable cam-grooves 22^a, provided in the disks 22, that are 35 fixed to revolve with the driving-shaft 19. The cam-grooves 22^a are properly timed to release the die-jaws 4 at the instant the crimping of the ferrule edge is completed. 40 In order to start and stop the machine at will, I prefer to provide a suitable clutch by which to interlock the hub of the gear-wheel 19^a and the disk 22. This clutch and the means by which it is actuated may be of any 45 of the various well-known constructions.

While I have shown and described preferred forms of mechanisms which I have found in practice to be satisfactory to attain the desired results, yet I do not desire to confine myself 50 to the particular forms herein described, as other devices may be employed to accomplish the same results in substantially the same manner without departing from the spirit of my invention.

60 What I claim as my invention, and desire to secure by Letters Patent, is as follows:

1. In a device for attaching ferrules to the ends of shade-rollers and the like, the combination of a die formed with an opening of 65 slightly less diameter than the diameter of the

roller; means for holding a ferrule in alinement with said opening; means for forcing the end of the roller compressibly through the opening and into said ferrule; and means for increasing the size of the die-opening to permit withdrawal of the ferrule. 70

2. In a device for attaching ferrules to the ends of shade-rollers and the like, the combination of a die formed with an opening of slightly less diameter than the diameter of the 75 roller; means for holding a ferrule in alinement with said opening; means for forcing the end of the roller compressibly through the opening and into said ferrule; means for forcing the ferrule and roller back a short distance into said opening, thereby crimping the end of the ferrule; and means for increasing the size of the opening to permit the withdrawal of the ferrule. 80

3. In a device for attaching ferrules to the 85 ends of shade-rollers and the like, the combination of a die formed with an opening; said opening having rounded edges and being of slightly less diameter than the diameter of the roller; means for holding a ferrule in alinement with said opening; means for forcing the end of the roller compressibly through the opening and into said ferrule; means for forcing the ferrule and roller back a short distance into said opening, thereby crimping 90 the end of the ferrule; and means for increasing the size of the opening to permit withdrawal of the ferrule. 95

4. In a device for attaching ferrules to the 100 ends of shade-rollers and the like, the combination of a die composed of a pair of oppositely-disposed members formed with an opening between them, said opening being provided with rounded edges and being when the dies are closed of slightly less diameter than 105 the diameter of the roller; means for holding a ferrule in alinement with said opening on one side thereof; means for forcing the end of the roller compressibly through the opening and into said ferrule; means for forcing 110 the ferrule and roller back a short distance into said opening, thereby compressing the edge of the ferrule into the roller; and means for separating said die members to increase 115 the size of the opening, thereby permitting withdrawal of the ferrule. 120

5. In a device for attaching ferrules to the 125 ends of shade-rollers and the like, the combination of a die composed of a pair of oppositely-disposed slidable members formed with an opening between them, said opening being provided with rounded edges and being when the dies are closed of slightly less diameter than the diameter of the roller; means for holding a ferrule in alinement with said opening on one side thereof; means for compressibly forcing the end of said roller through said opening and into the ferrule; means for forcing the ferrule and the roller back a short distance into said opening, thereby compressing 130

the edge of the ferrule into the roller; a toggle-link pivotally secured to each of said die members; a pair of slideable bars each pivotally connected to one of said links and having at 5 its rear end a projection; together with cams having grooves adapted to receive said projections.

6. In a device of the class described, a driving-shaft; a pair of duplicate cams mounted 10 thereon; a pair of oppositely-disposed and slidably-mounted die members; devices operatively connecting each of said cams with a corresponding die member; a reciprocating plunger in the rear of said die members; a 15 cam mounted on the driving-shaft and adapted to actuate said plunger; said cam being so timed relatively to said pair of cams that the latter operate to separate the die members when the plunger-cam moves forward a short 20 distance, substantially as described.

7. In a ferruling-machine for shade-rollers and the like, the combination with the cam-actuated plunger and the properly-timed cam-actuated dies; of a driving-plunger adapted 25 to force the roller endwise between said die members and against the cam-actuated plunger; for the purposes set forth.

8. In a ferruling-machine for shade-rollers and the like, the combination with the cam-actuated plunger and the properly-timed cam-actuated dies; of a driving-plunger adapted 30 to force the roller endwise between said die members and against the cam-actuated plunger;

ger; and a chain having brackets adapted to receive the rollers and provided with means 35 for imparting intermittent movement to said chain.

9. In a device of the class described, means for alining rollers with a ferruling mechanism, said means comprising a pair of conveyer-chains mounted on conveyer-wheels and having brackets to receive the rollers; and means for imparting intermittent movement to said chain, comprising a ratchet-wheel secured to the shaft of the conveyer-chain wheels, a pawl 40 engaging the ratchet-wheel, and a series of 45 levers for actuating said pawl, the last lever of said series being adapted to contact with a properly-timed moving part of the ferruling mechanism. 50

10. In a device of the class described, means for forcing the roller into its ferrule, said means comprising holding means for the ferrule, a slideable plunger, a swinging lever pivoted to said plunger, a second lever adapted to contact with a properly-timed moving part of the ferruling mechanism; a link connecting said levers, and a spring for restoring the plunger. 55

In testimony whereof I affix my signature in 60 presence of two witnesses.

CLAUDE FLAGLER.
